UNITED STATES PATENT OFFICE.

ARGYLE CAMPBELL, OF CHICAGO, ILLINOIS. ASSIGNOR TO ENTERPRISE RAILWAY EQUIPMENT COMPANY, OF CHICAGO, ILLINOIS.

MEANS FOR DISCHARGING MATERIALS FROM RAILROAD-CARS OR OTHER SIMILAR CONTAINERS.

1,342,091.

Specification of Letters Patent.

Patented June 1, 1920.

Application filed July 5, 1919. Serial No. 308,736.

To all whom it may concern:

Be it known that I, ARGYLE CAMPBELL, a citizen of the United States, residing at Chicago, in the county of Cook and State of Illinois, have invented a certain new and useful Improvement in Means for Discharging Materials from Railroad-Cars or other Similar Containers, of which the following is a full, clear, concise, and exact description, reference being had to the accompanying drawings, forming a part of this specification.

This invention relates to improvements in means for discharging materials from a railroad car or other similar containers.

In the carrying of grain and other bulk materials in railroad cars, great difficulty has heretofore been experienced in providing suitable means for effecting the discharge of the grain or other material from the cars. It is the usual practice to load grain and the like in ordinary box cars and the usual side door openings are most frequently closed by nailing a series of planks across the door openings. To unload the car, it is necessary to chop away some of these planks and in so doing, considerable grain is lost, chips of wood becomes mixed with the grain and there is of course a loss of the planks which are chopped. While it is true that many attempts have been made to provide suitable grain doors applicable to box cars, the same have not found favor with the railroad companies.

Some box cars have been made that are provided with hoppers suitable for effecting discharge of grain and like materials but these cars are comparatively few in number and involve an additional expense to the railroad companies which the latter cannot ordinarily afford. Furthermore, these grain hopper cars, so-called, are so designed that they may be built only as new cars and no satisfactory means has heretofore been designed, so far as I am aware, of converting old ordinary box cars into cars suitably adapted for discharging grain without the destruction of all or part of the usual planks nailed across the side doors of the car to form the grain closure.

One object of my invention is to provide a simple and relatively inexpensive device which may be either incorporated in new

box cars or readily and cheaply applied to ordinary box cars now in service and which will afford an effective means of discharging sufficient grain from the loaded car to permit the removal or opening of the usual side door closures of the car without destructive effects on such doors.

Another object of the invention is to provide a discharge chute applicable to box cars and other containers employed for carrying grain and like bulk materials, which chute is provided with closures at its entrance and discharge ends to thereby avoid any possible loss of the grain from leakage during transit.

Still another object of the invention is to provide a chute of the character above described which may be manufactured, shipped, and applied to cars as a unit or single article of manufacture and without necessitating any elaborate or expensive changes on the car to which it is applied.

Other objects of the invention will more clearly appear from the description herein-after following and embraced in the claims.

In the drawings forming a part of this specification Figure 1 is a vertical sectional view taken transversely of a box car showing my improvements in connection therewith, the section being located midway of the car and passing through my improved discharge chute. Fig. 2 is a part vertical sectional view, part end elevational view and illustrating more particularly the details of construction of the chute and operating mechanism. Fig. 3 is a side elevational view of a portion of a car and of the improved discharge chute. Fig. 4 is a view similar to Fig. 3 but upon a somewhat smaller scale and illustrates a greater portion of the side of the car and the relation of the location of my improved discharge chute with respect to the usual side door opening of a car. Fig. 5 is a view similar to Fig. 2 illustrating another embodiment of my invention. And Fig. 6 is a view similar to Fig. 1 but showing the construction illustrated in Fig. 5.

Referring first to the construction illustrated in Figs. 1, 2, 3 and 4, 10 denotes one of the center sills of a car, 11 the permanent or fixed flooring of a car, 12 the usual side door opening, and 13 a pivoted floor door,

Said floor door 13 is shown in horizontal position in Fig. 1 where it forms a part of the floor of the car when the latter is used as an ordinary box car for the carrying of package freight or other freight not of a fluid character. Said door 13 is pivoted along its outer edge as indicated at 14 so that it is adapted to be swung to a vertical position as indicated in Fig. 4, to form a grain-closure for the side door opening 12.

My improved discharging arrangement is designated generally by the reference A. Said device is composed, broadly, of an upper member 15 preferably in the form of a casting, a lower chute proper 16 preferably in the form of sheet metal, an upper door closure 17, a lower door closure 18, and door operating means hereinafter specifically described.

20 The upper member 15 is preferably rectangular in cross section and is provided on all sides thereof with integral laterally projecting lugs 19-19. The outer lugs 19, *i. e.* those lugs 19 located substantially beneath the side wall of the car, are supported by an angle iron 20 extending lengthwise of the car in the nature of a side sill and forming a part of the underframe of the car. The inner lugs 19 are supported by 25 and riveted to a longitudinally extending Z-bar 21 suitably united to the floor or underframe of the car and, in some instances, constituting an intermediate sill of the car underframe. The side lugs 19 are supported 30 on and riveted to transversely extending angle irons 22-22 suitably united to the framing of the car. As will be understood, the fixed or permanent flooring of the car 11 is suitably cut away to accommodate the 35 chute as shown by Figs. 1 and 2.

The sheet metal portion 16 of the chute A is riveted at its upper end to the member 15 and is formed with a deflection or incline adapted to direct the discharge of the grain 40 or other material to the center of the car, *i. e.*, between the rails of the track. At its lower end, the sheet metal section 16 has secured thereto a mouth casting 23 extending around all sides thereof and riveted 45 thereto. Said casting 23 on three sides thereof has a beveled flange mouth indicated at 24. Along its upper edge, said casting 23 is formed with a curved flange 25 concentric with the pivot 26 of the door 18. The door 50 18 is formed on three edges thereof with beveled flanges 27 coöperating with the beveled flanges 24 of the casting 23 and along its upper edge, the door 18 is formed with a convex flange 28 coöperable with the concave flange 25. In this manner, it is evident that I provide an effective grain seal 55 at the discharge end of the chute.

The door 17 is pivotally mounted on the member 15 as indicated at 29 and is adapted 60 to swing downwardly within the chute. Co-

operable with the edges of the door 17 are inwardly extending flanges around the edges of the member 15, said flanges being indicated at 30 and, together with the door 17, forming a supporting surface for the grain or other loading of the car.

For operating the doors 17 and 18, I preferably employ the following device. Secured to the outer under side of the portion 16 of the chute are end brackets 31-31 and 75 intermediate brackets 32-32. Rotatably mounted on said brackets 31 and 32 is an operating shaft indicated at 33. Rigidly associated with the shaft 33 are duplicate levers 34-34 which extend through suitable 80 slots provided in the brackets 32-32, to the interior of the chute. Pivots attached to the upper ends of the lever arms 34 as at 35 are links 36. The latter are in turn pivotally connected at their upper ends 85 to suitable lugs 37, formed on the under side of the door 17. The levers 34 and links 36 and their attachments to the shaft 33 and door 17, respectively, are so arranged that the levers and links form supporting struts 90 for the door 17 when the latter is in closed position. Associated with each lever 34 and the shaft 33 is an arcuate flange 38 disposed as most clearly shown in Fig. 1. Said arcuate flanges 38 correspond in width to the 95 slots provided in the brackets 32 so that, as the levers 34 swing to the dotted position shown in Fig. 1, said flanges 38 will form an effective seal at all times to prevent any discharge of the grain through the slots of 100 the chute.

To operate the lower door 18, I employ links 39 which are pivotally connected as indicated at 40 to the respective lever arms 34 and to adjustable bolts 41 mounted in the 105 door 18. It is evident from the foregoing that the opening and closing and locking of the doors 17 and 18 will always be simultaneous.

To operate the shaft 33 in a convenient 110 manner from the side of the car, I provide a suitable pawl and ratchet mechanism as follows. At one end of the shaft 33 and just beyond the outer face of the corresponding end wall of the chute, I secure a ratchet 115 wheel 42 to the shaft and oscillatably mount on said shaft a manually operable lever or handle 43. Said lever 43 is provided with a pivoted pawl 44 coöperable with the ratchet wheel 42. The lever 43 is held, 120 when not in use, by a pivoted latch 45.

To lock the shaft 33 against accidental rotation during movement of the car, I provide a locking dog 46 pivotally secured to the casting 23 as indicated at 47 and coöperable with said dog 46 is a cam lock 48 pivotally attached to the chute as indicated at 49.

From inspection of Fig. 4, it will be noted that the discharge or grain chute is dis-

posed opposite and closely adjacent to the side door opening of the car. With this arrangement, when the car is to be unloaded, the operator merely releases the shaft 33 so as to permit the doors 17 and 18 to swing open as indicated by the dotted lines in Fig. 1. This permits discharge of a sufficient amount of grain immediately behind the side door opening closure to relieve the latter from the pressure of the grain behind it so that said side door opening closure may be readily opened without destroying the same. This is true whether the side door opening closure is in the form of a pivoted floor door as I have described, or in the form of the usual nailed planks or in some other form. It will also be noted that my improved means can be moved, shipped and applied as a unit to either new or old cars at very small expense over and above the cost of the chute itself. In this way, the utility of ordinary box cars now in service may be greatly increased and furthermore without adding any excessive unproductive or dead weight to the car.

By providing the lower door 18 on the chute, any grain which may accidentally leak past the upper door 17 will be caught within the chute and thereby saved. Furthermore, the lower door 18 always provides an effective visual evidence of the condition of the chute and so long as it remains closed, observers may know that accidental loss of grain cannot take place. In the event said lower door 18 appears open while the car is in transit, a warning is thereby obtained to look to the chute to ascertain whether or not any grain is being accidentally lost. The door 18 furthermore forms an effective weather seal for the chute and the operating mechanism and keeps the interior of the chute clean so that no foreign matter will become mixed with the grain when it is being discharged from the car. Referring next to the construction illustrated in Figs. 5 and 6, the same general principles are employed.

In this form, the chute designated generally by the reference A' is preferably cast as a single piece as clearly shown in Fig. 6. In this instance, the chute is formed to direct the discharge of the grain to the side of the car, *i. e.*, outside of the rails. In the construction shown in Figs. 5 and 6 the upper end of the chute A' is left flush with the fixed floor 111 and no pivoted floor door is utilized. The chute A' is attached to the underframing of the car by suitable means as for instance by the laterally extended lugs 119 supported on and riveted to angle irons 122. Centering blocks 50 extend along the inner and outer sides of the chute, said blocks being bolted to the angle irons as indicated at 51. A longitudinally extending angle iron 120 is provided to which the

chute A' may be directly riveted as indicated at 52.

The upper door 117 of the chute is arranged and operated substantially the same as the door 17 shown in the other constructions, *i. e.*, the door 117 is pivotally supported on the casting A' and is operated by a link 136, lever arm 134 carried by a shaft 133. The shaft 133 in the present construction is mounted in suitable bearing brackets 75 131 preferably cast integral with the casting A'. A similar arcuate flange 138 is employed to effectively seal the opening through the chute to accommodate movements of the door operating mechanism. 80 Also, to form a backing or abutment for the lever 134, an integral shoulder 53 may be cast on the interior of the chute, the shoulder 53 being so located that when the door 117 is in closed position, the pivotal connection between the lever 134 and the link 136 will be slightly to the right of the line joining the pivotal connection of the link 136 with the door 117 and the center of the shaft 133. 85

In the construction shown in Figs. 5 and 6, I preferably eliminate the pawl and ratchet mechanism and employ a simple lever 143 rigid with the shaft 133, a pivoted locking dog 146 and a pivoted locking cam 95 148. For coöperation with the dog 146, the lever 143 is provided with a radial arm 54 as clearly shown in Fig. 5. 90

In some instances, where the door at the discharge end of the chute is readily accessible, it may not be necessary to provide means for operating said door. I have shown in Figs. 5 and 6 a lower door closure 118 pivotally attached to the chute proper as indicated at 126, and to lock said door 118 in closed position I provide a slidably mounted in suitable lugs 153 100 153 slidably mounted in suitable lugs 154 cast on the outer side of the door 118. Said pin 153 at its lower end is tapered as indicated at 55 to facilitate its entrance into a 110 coöperating opening 56 formed on an adjacent projecting flange of the chute proper. As will be evident from inspection of Fig. 6, when the locking pin 153 is in position shown, the door 118 will be held in closed 115 position and may be opened by merely lifting the pin. To prevent tampering with the parts, the pin 153 may be perforated as indicated at 57 to accommodate the usual railway lead seal. As will be understood, the door 118 and the chute proper are so formed at the discharge end as to effect a grain seal as described in detail in connection with the construction shown in Figs. 1 to 4. 120

It will be evident that the arrangement shown in Figs. 5 and 6 possesses the same advantages and obtains the same results as hereinbefore set forth in connection with the construction illustrated in the other figures of the drawing. 251

Although I have herein shown and described what I now consider the preferred methods of carrying out the invention, the same are merely illustrative and I contemplate all changes and modifications as come within the scope of the claims appended hereto.

I claim:

1. In a car adapted for the carrying of grain and other materials in bulk and having an opening in the floor thereof, the combination with a chute extended vertically downwardly from said floor opening for a portion of its length and having its lower end deflected to one side of the vertical, of a top door pivotally mounted on said chute and arranged to close the upper end thereof when in horizontal position, means for operating said door including elements located within the chute and a lever located outside of and carried by the chute, a lower door for closing the discharge end of the chute, and means for retaining said lower door in closed position.
2. In a car adapted for carrying grain and other materials in bulk and having an opening through the floor thereof, the combination with a chute extending downwardly through said floor opening, of top and bottom doors for closing the upper and lower ends of the chute, and mechanism for operating said doors simultaneously both in an opening direction.
3. As an article of manufacture, a device for effecting discharge of grains or other bulk materials from a car or other container and adapted to be applied as a structural unit, said device comprising a chute proper, top and bottom doors pivotally attached to the chute and arranged to close the entrance and exit ends of the chute, respectively, mechanism for operating said top door including a shaft, lever arm, link and operating handle, means for retaining said bottom door in closed position, and coöperating grain sealing flanges on said chute and bottom door.
4. As an article of manufacture, a device for discharging grain or other materials in bulk from cars or other containers and adapted for application thereto, said device comprising, a chute proper, an upper door pivotally mounted within the chute, a shaft disposed outside of the chute, means interposed between said shaft and said door for operating the latter, a part of which extend through the wall of the chute, means for maintaining a grain seal where said first named means extend through the wall of the chute, a lower door pivotally secured to the chute, means for locking said lower door in closed position, and coöperating means on said lower door and chute for maintaining a grain seal therebetween.
5. As an article of manufacture, a device

for effecting discharge of grains or other bulk materials from a car or the like and adapted to be applied as a unit to the car, said device including, a chute proper having an upper vertical section and a lower laterally deflected section with openings at the top and bottom, the upper part of the chute being arranged to be located flush with the floor of a car and secured thereto, a pivoted door adapted to close the top of the chute, a pivoted door adapted to close the bottom of the chute, and mechanism for sustaining said top door in closed position, said mechanism including an operating shaft supported by the chute, and a manually operable lever on said shaft disposed outside of the chute and adapted to be operated from the side of the car when the chute is in place.

6. In a car adapted for carrying bulk material, means for discharging bulk material from the car, said means including a downwardly displaceable floor door in the car, a chute beneath said door, mechanism for operating said door, said mechanism including elements disposed within the chute and elements extended to the exterior of the chute, the chute being suitably recessed to accommodate those elements extending to the exterior thereof, and means for substantially sealing said recessed portions of the chute in all positions of the said mechanism.

7. As an article of manufacture, mechanism adapted for application to a box car or other receptacle suitable for containing material in bulk such as grain, said mechanism comprising a chute, a door for closing the top opening of said chute, the door being movable to an open position within the chute, and devices for operating said door, said devices being supported by the chute and including a rotatable shaft, connections between the shaft and door located within the chute, and a manually operable lever coöperable with the shaft.

8. As an article of manufacture, mechanism adapted for application to a box car or other receptacle adapted for containing bulk material such as grain, said mechanism comprising a chute, a pivoted door adapted to close the top opening of the chute when in closed position and arranged to swing within the chute when opened, and devices for operating and supporting said door in closed position, said devices being supported entirely by the chute and including a manually operable lever.

9. As an article of manufacture, mechanism adapted for application to a box car or other receptacle adapted to contain bulk material such as grain, said mechanism comprising a chute open at the top and bottom, a pivoted door arranged to close the top opening of said chute, said door being ar-

- ranged to swing within the chute when moved to open position and devices for operating and supporting said door in closed position, said devices including a shaft operable from the exterior of the chute, and connections between said shaft and the door, said shaft and connections sustaining the load on the door when the latter is in closed position.
10. In a railroad car, in combination, a chute, a hinged door therefor, a link connected to said door, an arm connected to said link and a shaft for rotating the said arm, the said shaft being mounted upon the chute.
11. In a railroad car, the combination with an opening in the floor thereof, of a chute leading from said opening, a door for closing the upper end of said chute, means for operating said door, including a shaft and a link connecting the shaft to the door, the shaft being mounted upon the said chute.
12. In a railroad car having a floor, an opening in said floor, a chute leading from said opening, the said chute being provided with a door and having means for opening and closing the same, the said means including a link connected to the door, a shaft, an arm mounted upon said shaft and means connecting the arm to the link, the chute being provided with an opening for the passage of said arm therethrough, the said arm being provided with a lug adapted to fill said opening on rotation of the arm.
13. In a railroad car, in combination, a chute having a door, and means for operating said door, said means including a shaft mounted outside of the chute, an arm mounted on said shaft, an opening through said chute for the passage of the arm, a link within the chute connected to said door and a connection between the said arm and link.
14. In a railroad car, in combination, a chute having a door, and means for operating said door, said means including a shaft mounted outside of the chute, an arm mounted on said shaft, an opening through said chute for the passage of the arm, a link within the chute connected to said door, a connection between the said arm and link, and a lug upon said arm adapted to close the said opening on rotation of the arm by said shaft.
15. In a railroad car, the combination with an opening in the floor thereof, of a chute leading therefrom, a swinging door closing said chute, a link connected to said door, a shaft mounted outside the said chute, an arm mounted upon the said shaft, an opening through the said chute for the passage of said arm, means connecting the link with the arm and an arcuate lug upon said arm adapted to maintain a closure of said opening on rotation of the arm.
16. In a railroad car, in combination, a door, a floor opening near said door, a chute leading downwardly from said opening and angularly deflected at its lower end, the said chute being secured to the car and having a door at its upper end, the said chute being provided with mechanism for operating said door, the mechanism including a link mounted within the chute and attached to the door, a shaft mounted outside the chute, an arm mounted on said shaft, the chute having an opening for the passage of said arm therethrough and means for connecting said arm to the said link within the chute.
17. As an article of manufacture, a discharge chute adapted for application to a car as a unitary structure, said chute having an admission opening at the top thereof, a vertically extending inclosed section immediately below the top opening and an inclined inclosed section below said vertical section, the chute having a discharge opening at the lower part of said inclined section, the top of the chute being adapted to be disposed flush with the upper surface of the car floor and with the vertical section thereof extending through the floor, a door for closing said top opening, the door being mounted on said chute and displaceable to a position within said vertically extending section of the chute when opened, and means for supporting said door in closed position including, an operating handle located adjacent said discharge opening.
18. As an article of manufacture, a discharging device adapted for application to a car, said device comprising, a chute proper having an opening in the top and an opening at the bottom, a door for closing the top opening, the door being mounted on said chute and displaceable to a position within the latter when opened, and means for supporting said door in closed position, said means being carried by said chute and including a shaft and a toggle connection between the shaft and door, said chute having a shoulder against which one element of the toggle is adapted to bear when the door is in closed position thereby adapting the toggle to act as a strut between the shaft and the door when the latter is closed.
19. As an article of manufacture, a device for discharging grain or other materials in bulk from cars and adapted for application thereto in alignment with a floor opening thereof, said device comprising: a chute having a vertically extending upper section adapted to have the top thereof positioned in said floor opening and at its lower end being deflected to one side of the vertical; a top door pivotally mounted on said chute and arranged to close the upper end thereof when in horizontal position; a lower door pivotally attached to the chute and adapted to close the discharge end of the chute; a

lever pivotally mounted on said chute; a link pivotally connected at one of its ends to the free end of said lever and at its other end to the said top door; and a link pivotally connected to said lever intermediate the ends of the latter and to said pivoted lower door, whereby, both the top and lower doors are

adapted to be opened and closed simultaneously.

In witness that I claim the foregoing I 10 have hereunto subscribed my name this 13th day of June 1919.

ARGYLE CAMPBELL.
